UNITED STATES PATENT OFFICE.

OSCAR FALKENWALDE, OF BALTIMORE, MARYLAND.

GASEOUS-FUEL BURNER.

SPECIFICATION forming part of Letters Patent No. 733,828, dated July 14, 1903.

Application filed April 21, 1903. Serial No. 153,628. (No model.)

To all whom it may concern:

Be it known that I, OSCAR FALKENWALDE, residing in Baltimore city, State of Maryland, have invented a new and Improved Gaseous-Fuel Burner, of which the following is a specification.

My present invention relates to improvements in that type of gaseous-fuel or hydro-carbon burners for use in the fire-boxes of ordinary cooking stoves or ranges for hot air or water furnaces, and it more particularly seeks to provide an improved type of burner of the character stated embodying the generic features of the burner disclosed in my Patent No. 715,467; and it primarily has for its object to provide certain improvements on the burner disclosed in my patent aforesaid whereby a more practically operating burner is provided which can be fired by use of crude or refined volatile oils, whereby the same is especially well adapted for heating steam-boilers of marine engines and for other analogous uses.

My present invention in its generic nature comprehends a casing or body apertured transversely and having a longitudinal conical bore tapering from its entrant to its discharge end, air-inlets in the casing opening into the top and the bottom of the said bore, a generator-pipe mounted within the heat zone of the burner, and a valved ejector connected to the said pipe and held to discharge into the entrant end of the conical bore in the burner-body.

My present invention in its more complete form comprises a body having a longitudinally-extended conical bore, transverse apertures bisecting said bore, air-inlets in the said body communicating with the bore, a generator-pipe held in the hot zone of the generator, and an ejector-valve positioned with respect to the entrant end of the conical bore to discharge the vaporous sprays at an angle to the longitudinal axis of the said conical bore, whereby to eject the vapor against the wall of the bore in a manner to cause the same to pass through the said bore in a staggered direction to reduce danger of carbonizing and producing a more complete combustion of the volatile substance.

In its more subordinate features my pres-

ent invention embodies certain improvements in the needle or ejector valve, the base-casting or body-support, as also other details of construction, all of which will hereinafter be fully explained, and specifically pointed out in the appended claims, reference being had to the accompanying drawings, in which—

Figure 1 is a perspective view of my improved gaseous-fuel burner. Fig. 2 is a longitudinal section thereof, parts being in side elevation. Fig. 3 is a transverse section thereof; and Fig. 4 is a perspective view of the bottom casting, hereinafter referred to.

In my present construction the body or casting 1 of the burner has an external shape substantially that shown in my patent before referred to, and the same is detachably supported on the base-casting 2, the peculiar construction of which forms a special feature of my present invention and will be presently described.

The longitudinal bore or flue 10 in my present construction of burner extends from the rear end to a point in line with the base c of the tapering head or end 1^a of the body, and the said bore is made conical and tapers from the entrant to the exit end, as clearly shown in Fig. 2.

The object in making the bore 10 cone-shaped is to provide an increased draft in the direction of the discharge end, create a greater increased suction of air into the retort through the air-inlets 3 3^a, disposed relatively in the bottom and the top of the body 1, whereby to produce, as it were, a Bunsen-burner action for the mixture of the air and gas within the retort.

b b designate the transversely - arranged burner holes or flues, which extend through the body 1 and bisect the conical bore 10, the said cross-flues being so arranged to not unnecessarily retard the suction or intake of the air through the inlets 3 3^a.

The generator-pipe G in my present case includes a horizontal portion which extends over the top of the body 1 within the hot zone thereof and is detachably supported in the vertical extensions 1^a, cast with the said body 1.

To the rear end of the pipe-section G is detachably secured an elbow g^x, to the pendent

end of which is detachably connected the 5 ejector or needle valve 5, the peculiar construction of which and its relation with the conical bore 10 is best shown in Fig. 2, by reference to which it will be seen the same comprises a casing consisting of a vertical portion 5^a and the horizontal portion 5^b, which is inclined at an acute angle with respect to the longitudinal axis of the said bore 10, where-
10 by to eject the volatile spray into the bore against the upper wall thereof, as indicated by the dotted-line portion x, such arrangement of parts being provided to prevent the direct flow or passage of the said volatile spray through the bore 10 and cause the said fuel-spray to be deflected in a staggered direction against the upper and lower walls of the bore in the manner indicated by the dotted lines x' x² x³. By thus passing the volatile fluid into the bore or retort 10 the same is sufficiently retarded in its passage there-
20 through to provide for a complete combustion thereof of the gaseous vapor with the air drawn in through the upper and lower air-in-
lets.
25

By checking the direct flow of the gaseous vapors, as stated, I find from practical experience that danger of carbonizing within the retort is materially reduced thereby and a
30 perfect combustion is effected, and in conse-
quence thereof a greatly-increased heat pro-
duction from a given quantity of fuel is ob-
tained over what is possible in the arrange-
ment of the fuel-ejector and retort shown in
35 my patent aforesaid.

The valve-casing in my present construction has the usual screw-tap to receive the collar 6, and the needle 7 is also of the usual type, except its shank 7^a is provided with an
40 annular shoulder 7^b to prevent the possibility of accidentally turning the valve back to such a distance as to entirely disengage its threads 7^c from the internal threads 5^c in the casing, and thereby overcome the danger of
45 pulling the valve out of its casing during the operation of adjusting the valve for controlling the discharge.

Another and important advantage in ejecting the gaseous fuel into the retort or bore 10
50 in a staggered manner, as described, is that it admits of using either crude or refined oil in my present construction of burner. When arranged for using crude oil, the jet or escape passage of the valve is made somewhat
55 smaller than is necessary in the use of refined oil, and to provide for a sufficient admixture of air the top of the feed has a greater number of air-inlets than is required when refined oil is used.

60 I have provided for an economical manufacture of the generator devices and for readily cleaning the same.

65 By referring now to Fig. 2 it will be noticed the pipe G joins with a T-coupling 8, provided with a detachable screw-plug 8^a in

the top and with a screw-tap at the bottom to receive the short pipe-section 9, with which connects a second section 12, to which the fuel-feed pipe P joins, and the said section 12 also has a screw-tap 12^a in the bottom. 70

The pipe G and the members 9, 12, and 18 are filled with a fluid-absorbing fireproof material in a comminuted form, as indicated by 9^x, 12^x, and G^x, which is packed sufficiently loose so as not to prevent the flow of the fluid, 75 but sufficiently tight to screen the fluid and effect a thorough distribution of the minute particles thereof.

The bottom casing in my present construc- 80 tion (best illustrated in Fig. 4) consists of a body having a series of vertically-projected angle-lugs 2^a 2^a, which form foot-rests to support the burner-body 1 sufficiently above the casting 2 to provide for a free circulation of air thereunder, which enters through the 85 longitudinal openings 2^c 2^c in the body 2, oppositely disposed one at each side of a longitudinal channel or trough 2^d, which joins a collecting-pocket 2^e at one end of the body 2 and a pocket 2^f at the opposite end of said body 2, which extends under the ejector-valve and is intended to collect the drippings therefrom. 90

By constructing the burner base or body 2 in the manner stated the asbestos lining 95 necessary in the form of base shown in my other patent is not required, for the reason that the drippings in the pocket 2^f will flow into the central trough 2^d, be conveyed under the hot burner-body 1, and consumed. 100

The bottom casting 2 in my present invention is also wider than the burner-body 1, whereby to provide lateral extensions 2^x, and these extensions have longitudinal channels 2^z, that dip or slant from the pocket 2^f to 105 pocket 2^e, (see dotted lines, Fig. 2,) and the said channels 2^z are so disposed under the outer ends of the cross-flues b as to catch any drippings from the said flues, whereby to convey the same from the pocket 2^e, from whence they pass to the central trough or 110 channel 2^d and are consumed, thus preventing the waste of any of the fuel.

In the complete form my improved burner also includes a water-drip means for producing water-dust in the retort to assist in reducing carbonization in the retort 10 and for minimizing the disagreeable blowing noise incident in the use of this type of burner. The said water feed or drip means comprises a 115 tank supported at any desired point, which has a pendent or gravity discharging-pipe 15, provided with a valve 15^a, terminating in a nozzle 15^b, that extends into the entrant end of the bore 10 into the plane of the discharge 120 from the ejector or fuel-feed valve to drop the water into the vaporous discharges, in which the water diffuses, and to materially aid in separating the carbon and nitrogen and creating a more perfect decomposition of the 125 130

the handle, as shown at Figs. 9 and 10, and which is constructed with a hook *f* at its outer end, which descends into a notch *g* in the back *Z* and thence into the corresponding notch in the saw *X*, as shown more particularly at Figs. 9 and 10, so that by reason of that part of the back *Z* which is nearest to the saw-handle being constructed with a slit therein corresponding in thickness with the thickness of the saw *X* the back *Z* becomes firmly fixed to the saw *X*, both at its front and rearward ends, while the back *Z* operates in the broad openings *h h*, respectively, in the upper part of the two vertical slides shown at Figs. 9, 11, and 12, which slides are marked *i i* in not only Figs. 9, 11, and 12, but in Figs. 3 and 6 of my improved miter-box also, thereby enabling an ordinary crosscut-saw to be operated after the manner of a tenon-saw in miter-boxes, also admitting of the ready removal of the back or frame *Z* when it is required to use the saw *X* for its ordinary purposes. The rear end of the back or frame *Z* is further held securely in place by entering notches *k*, one on each side of the blade *X*, in the handle *l*, as shown at Fig. 9.

Having now described the nature of my present improvements and the best system, mode, or manner with which I am at present acquainted for carrying the same into practical effect, I desire to observe in conclusion that what I consider to be novel and original, and therefore claim as the invention to be secured to me by Letters Patent, is as follows:

1. In a miter-box having a circular table and leaves or backs movable angularly upon or about a vertical axis which is the center of the circular table, the central pivot projecting downward from the under part of the circular table, upon which pivot the two rings each having an arm to which each leaf or back is connected are carried, and all operating in the manner and for the purposes substantially as set forth.

2. In a miter-box having a circular table, the circular-stand connection whereby the circular stand is attached to the same downwardly-projecting central pivot upon which

the rings and arms which carry the leaves or backs are pivoted, by means of which connection the rings and the circular stand are all carried by and revolve in common upon this one and the same central pivot, so that the 55 rings and the circular stand are all held by this connection in permanent operative attachment to the central pivot of the miter-box, substantially as hereinbefore set forth.

3. The supplementary stop with incline 60 face toward the leaves or backs of the miter-box, for giving support to the rear face of half-moldings being cut in my improved circular miter-box, said supplementary stop comprising a metal strip bent to form an upward 65 arm to engage the work, an outward arm and a flat or horizontal foot, substantially as hereinbefore described, having a slot in its horizontal flat foot, which passes under the shoulder of the screw or nut which on being tightened 70 fastens the supplementary stop in the required position, substantially as set forth.

4. The combination of the crosscut-saw, the removable back or frame applied to the crosscut-saw, and the saw having a notch in 75 the front end thereof, the back or frame having a slit in the outer end with transverse pin for engaging with notch in the front end of the saw, the handle end of the frame or back having the slit in the under side for engaging 80 with the handle end of the saw-blade, the handle having the notches in either side whereto the rear ends of the back or frame enter, when the back or frame and saw are placed together, and the back and saw-blade 85 both having notches whereto the catch of the spring attached to the handle of the saw-blade enters for holding the parts together; also the spring attached to the handle of the saw, the whole operating together in the manner and for the purposes substantially as hereinbefore described.

In testimony whereof I, the said RUFUS HERRICK DORN, have hereunto set my hand and seal, this 2d day of July, 1901, in the presence of two subscribing witnesses.

RUFUS HERRICK DORN. [L.S.]
